(57) **CLAIM**

The ornamental design for a doorbell chime cover, as shown and described.

DESCRIPTION

FIG. 1 is a perspective view of a doorbell chime cover constructed in accordance with an embodiment of the present invention;

FIG. 2 is a front view of the doorbell chime cover shown in FIG. 1;

FIG. 3 is a rear view of the doorbell chime cover shown in FIGS. 1 and 2;

FIG. 4 is a top view of the doorbell chime cover shown in FIGS. 1-3;

FIG. 5 is a bottom view of the doorbell chime cover shown in FIGS. 1-4;

FIG. 6 is a right side view of the doorbell chime cover shown in FIGS. 1-5; and,

FIG. 7 is a left side view of the doorbell chime cover shown in FIGS. 1-6.

The broken lines are for illustrative purposes only and form no part of the claimed design.
